DOUGALD MCEACHERN, OF DUNCAN, BRITISH COLUMBIA, CANADA

WATERPROOF JOINT

Application filed July 10, 1931. Serial No. 549,958.

My invention relates to improvements in water-proof joints, and it consists in the constructions, combinations, and arrangements herein described and claimed.

In mining operations where explosives, such as dynamite and fuses for detonating the same are used, it is customary to attach the fuses to a detonating cap. Where the charge is to be used under water or in places where water is liable to accumulate it is very necessary that the joint between the fuse and the cap be water-tight. Various attempts have been made to render this joint water-tight, such as by crimping the cap onto the fuse or by putting grease over the joint. In crimping the end of the cap over the fuse there is liability of cutting or choking it while the application of grease may be knocked off by the concussion of a discharge in a hole in the vicinity.

An object of my invention is to provide a water-proof joint which can be effected quickly and which will not choke the fuse nor will it be knocked off by an explosion in the vicinity.

A further object of my invention is to provide a water-proofing means for a joint which may be quickly applied and which will absolutely prevent the water from entering the joint.

A further object is to provide means for water-proofing a joint of this kind in which an elastic substance, such as a rubber band, is provided with a wire terminal that can be wrapped around the fuse and which when wrapped does not require tying or other means to hold it in position.

Other objects and advantages will appear in the following specification, and the novel features of the invention will be particularly pointed out in the appended claims.

My invention is illustrated in the accompanying drawing forming a part of this application and in which:

Figure 1 is a side view, showing a fuse and a cap completely covered with the water-proofing means;

Figure 2 is a similar view, showing the joint between the fuse and the cap covered with the water-proofing means;

Figure 3 is a view, showing the water-proofing means in section;

Figure 4 is a perspective view of the water-proofing means;

Figure 5 is a view of a stick of dynamite, showing the use of the water-proofing means as a connecting and holding means for a fuse and a cap which is inserted into the stick of dynamite; and

Figure 6 is a similar view, but showing the cap and fuse going directly into the end of the stick of dynamite.

In carrying out my invention I make use of a flat band 1, which is preferably of rubber. This band 1 as will be observed is elongated and is provided at its end with a wire 2. This wire is passed through one end and is twisted, as shown at 2^a. The substance of the wire is such that it is easily bent but remains in the position in which it is bent, as distinguished from a wire which has been tempered to be used as a spring.

In Figure 3 I have shown the fuse 3 as extending into a cap 4 up to the detonating charge 5. In this figure the body portion 1 of the rubber band is wound around the outside of the cap and onto the fuse passing the joint at 6, which indicates the end of the cap. The wire 2 is continued on by winding it, and when it is wound it has the position shown in Figure 2. In this figure it will be observed that the band has been wound so that the different convolutions overlap. In winding the band it is stretched and each convolution tends to press the one below it so that the rubber band effectually hugs the joint, thereby keeping out the moisture.

By continuing the winding with the wire, the latter is twisted around the fuse 3, the end of the wire remaining close to the fuse so that there is no tendency for the rubber winding to unwrap.

This produces a joint which can be very quickly applied because it does not require tying or holding in any other way than merely winding the terminal wire around as stated.

In Figure 1 I have shown the cap as well as the fuse wrapped with the rubber band. It is sometimes advisable to place the cap

alongside of the charge, such as a stick of dynamite. If the cap is wrapped as shown in Figure 1, it will not only serve as a protection for the joint between the fuse 3 and the cap, but it will protect the cap by a soft resilient covering when the hole is tamped. It may happen, if a cap is not thus protected that in tamping, rocks or grit may be forced against the cap and cause a premature explosion.

In Figure 5 I have shown the water-proofing means used as a binding means rather than a water proofing means. In this figure the dynamite stick 7 has an angularly inclined opening, into which the cap 4 extends, this cap being connected with the fuse 3. The band 1 is wound around the end of the stick of dynamite and around the fuse and the end of the wire 2 is carried around the fuse so as to hold the band in position. This makes an effective connection between the fuse and the dynamite charge so as to prevent the pulling of the fuse and the detonating cap away from the dynamite.

In Figure 6 I have shown another modification, in which the cap instead of extending in at an angle extends directly into the dynamite stick along the central axis. In this form of the device the rubber is wound around the stick and the fuse and the wire 2 is continued around both, thus securely holding the fuse and the cap to the stick.

It will be seen that my invention has a double use. It may be used as a means for water proofing a joint or it may be used as a mere connecting means as in Figures 5 and 6. In each instance the wrapping of the band while it is stretched tends to grip the fuse or cap or the stick of dynamite tightly and by merely continuing the winding with the wire, the joint or connection is effected.

In applying the water-proofing means to the joint between the fuse and the cap it will be observed that it is not necessary to crimp the cap. In instances where caps have been crimped onto the fuse, the fuse has been choked to such an extent as to prevent the explosion. The liability of a misfire, due to a choked fuse is obviated in the present invention. The rubber band will cling tenaciously to the fuse and to the cap so that there is absolutely no chance of pulling the fuse from the cap, even though tension should be used.

I claim:

1. The combination of a joined fuse and detonating cap, of means for water-proofing the joint, said means comprising a rubber band wound on the fuse and cap, the layers of the band overlapping, and a pliable wire attached to one end of the band and wound closely to hold the band in position.

2. The combination of a joined fuse and detonating cap, of means for water-proofing the joint, said means comprising a water-

proof band covering the joint, the layers of the band overlapping one another, and a pliable wire attached to one end of the band and wound closely to hold the band in position.

3. As an article of manufacture, a water-proofing and connecting means comprising a resilient water-proof band, and a pliable wire attached to the end of the band, said wire being adapted to remain in any position in which it is bent.

4. The combination of a joined fuse and detonating joint, of means for water-proofing the joint, said means comprising a water-proof elastic band covering the joint, the layers of the band overlapping one another, and a pliable wire attached to one end of the band and wound closely around the fuse beyond the joint, the material of the wire being such that the wire will remain in the position in which it is bent.
